CLAIM

The ornamental design for fluorescent lamp tube with insulated ground strip, as shown and described.

DESCRIPTION

FIG. 1 is a perspective view of a fluorescent lamp tube with insulated ground strip showing my new design; FIG. 2 is a side view thereof showing the insulating strip along the right hand edge of the fluorescent tube in the Figure;

FIG. 3 is a side view thereof rotated 90° from the FIG. 2 view with the ground strip hidden from view; and, FIG. 4 is an end elevational view thereof, with the opposite end being a mirror image, except for the jagged edge of the insulated ground strip.
